Primary Examiner—Ted Shooman*Assistant Examiner*—Cheri Cohen[57] **CLAIM**

The ornamental design for the golf ball putting aid, as shown and described to be an original design as my own.

DESCRIPTION

FIG. 1 is a top plan view of a golf ball putting aid showing my new design;

FIG. 2 is a bottom plan view thereof;

FIG. 3 is a side elevation view thereof, the opposite side being a mirror image;

FIG. 4 is a front elevation view thereof, the opposite side being identical; and,

FIG. 5 is a top plan view thereof.

The broken line showing of the golf ball in FIG. 5 is for illustrative purposes only and forms no part of the claimed design.
